US00D617378S

(12) **United States Design Patent**
Skelding et al.

(10) **Patent No.:** US D617,378 S
(45) **Date of Patent:** ** *Jun. 8, 2010

(54) **TRANSACTION DEVICE WITH A GEM-LIKE SURFACE APPEARANCE**

(75) Inventors: **Dori K. Skelding**, Wilmington (DE);
Walter Brent Reinhard, Lansdale, PA (US)

(73) Assignee: **JPMorgan Chase Bank, N.A.**, New York, NY (US)

(**) Term: **14 Years**

(21) Appl. No.: **29/332,299**

(22) Filed: **Feb. 12, 2009**

(51) **LOC (9) Cl.** 19-08

(52) **U.S. Cl.** D19/10

(58) **Field of Classification Search** D19/1-34;

40/124.01-124.15, 672, 661, 726, 776, 617; 283/72, 74, 75, 103, 105, 106; 206/449; D21/385; D20/10, 22, 27, 40, 42, 11; D14/435-437; 235/487, 488

See application file for complete search history.

(57) **CLAIM**

We claim the ornamental design for a transaction device with a gem-like surface appearance, as shown and described.

DESCRIPTION

FIG. 1 depicts a perspective view of a front face of a transaction device with a gem-like surface appearance.

FIG. 2 depicts a front elevation view of FIG. 1.

FIG. 3 depicts a back elevation view of FIG. 1.

FIG. 4 depicts a side elevation view of FIG. 1.

FIG. 5 depicts an opposite side elevation view of FIG. 1.

FIG. 6 depicts a bottom plan view of FIG. 1.

FIG. 7 depicts an top plan view of FIG. 1.

FIG. 8 depicts a perspective view of a front face of a second embodiment of a transaction device with a gem-like surface appearance.

FIG. 9 depicts a front elevation view of FIG. 8.

FIG. 10 depicts a back elevation view of FIG. 8.

FIG. 11 depicts a side elevation view of FIG. 8.

FIG. 12 depicts an opposite side elevation view of FIG. 8.

FIG. 13 depicts a bottom plan view of FIG. 8; and,

FIG. 14 depicts an top plan view of FIG. 8.

The shading in the drawings is provided to illustrate surface color variations of the design and it is not intended to be illustrative of texture.

The broken lines in the drawings illustrate environmental structure on the article and form no part of the claimed design.
